(57) **CLAIM**

The ornamental design for a magnetic board game, as shown and described.

DESCRIPTION

FIG. 1 is a top perspective view of a design of a magnetic board of magnetic board game;

FIG. 2 shows a top view of the magnetic board of FIG. 1, with the bottom view being the same;

FIG. 3 shows a side edge view of the magnetic board of FIGS. 1 and 2, with all side edges being the same;

FIG. 4 is a top perspective view of a design of a magnetic tile piece of a magnetic board game for use with the magnetic board of FIGS. 1-3;

FIG. 5 shows a rear edge view of the magnetic tile piece of FIG. 4;

FIG. 6 shows a left edge view of the magnetic tile piece of FIG. 4.

FIG. 7 shows a top view of the magnetic tile piece of FIGS. 4-6, with the bottom being the same;

FIG. 8 shows a right edge view of the magnetic tile piece of FIGS. 4-7;

FIG. 9 shows a front edge view of the magnetic tile piece of FIG. 7;

FIG. 10 is a top perspective view of a design of a second magnetic tile piece of a magnetic board game for use with the magnetic board of FIGS. 1-3;

FIG. 11 shows a top view of the second magnetic tile piece of FIG. 10, with the bottom being the same;

FIG. 12 shows a right edge view of the second magnetic tile piece of FIGS. 10 and 11, with the left edge being the same;

FIG. 13 shows a front edge view of the second magnetic tile piece of FIGS. 10-12, with the rear edge being the same;

FIG. 14 is a top perspective view of a design of a third magnetic tile piece of a magnetic board game for use with the magnetic board of FIGS. 1-3;

FIG. 15 shows a top view of the third magnetic tile piece of FIG. 14, with the bottom being the same;

FIG. 16 shows a right edge view of the third magnetic tile piece of FIGS. 14 and 15, with the left edge being the same; and,

FIG. 17 shows a front edge view of the third magnetic tile piece of FIGS. 14-16, with the rear edge being the same.
